Des. 987

E. J. Delany & John Martino, of Philadelphia, Pa.
Assors to

Creson, Stuart & Peterson, of Philadelphia aforesaid,
Letters Patent No 987 - Dated Feby 16th 1858.

The schedule referred to in these Letters Patent and making part of the same

To all to whom these presents shall come.

Be it known that we, E. J. Delany and John Martino, both of the City and County of Philadelphia, and state of Pennsylvania, have invented or produced a design for stove plates which we call the "magic shield" a full and exact description of which is as follows. A. is the stove plate in the center of which is cast a deep intaglio device of a shield B. The tablet of the shield is plain and level and bears an inscription, in this case purporting to be the date of the patent.

The shield is environed with appropriate ornaments, but these are merely tributary to the chief design which is the intaglio shield. This device is attended with an incidental advantage, as the inward projection of the shield divides the draft to the boilers on either side, when used as the upper front

of a cooking stove.

What we claim as our design for stove plates, is End
the shield in intaglio, as herein set forth.
